DESIGN FOR AN ELECTRIC RANGE OR SIMILAR ARTICLE

Walter C. Ayers, Detroit, Mich., assignor to Electromaster, Inc., Detroit, Mich., a corporation of Michigan

Application October 3, 1938, Serial No. 80,209

Term of patent 14 years

To all whom it may concern:

Be it known that I, Walter C. Ayers, a citizen of the United States and a resident of the city of Detroit, in the county of Wayne and State of Michigan, have invented a new, original, and ornamental Design for an Electric Range or Similar Article, of which the following is a specification, reference being had to the accompanying drawing, forming a part thereof.

On the drawing the figure is a perspective view of the electric range showing my new design.

The other side or end of the range, not shown, is substantially plain.

I claim:

The ornamental design for an electric range or similar article, as shown and described.

WALTER C. AYERS.
